UNITED STATES PATENT OFFICE.

IDA A. GUTSELL, OF ITHACA, NEW YORK.

DESIGN FOR A PATTERN FOR PRINTED FABRICS.

SPECIFICATION forming part of Design No. 22,946, dated December 5, 1893.

Application filed September 5, 1893. Serial No. 484,870. Term of patent 7 years.

To all whom it may concern:

Be it known that I, IDA A. GUTSELL, of Ithaca, in the county of Tompkins, in the State of New York, have invented a new and useful Design for a Pattern for Printed Fabrics, of which the following, taken in connection with the accompanying drawing, is a full, clear, and exact description.

This is a design intended to be printed, painted or otherwise placed upon a suitable fabric as represented in the accompanying drawing which illustrates a piece of fabric with the obverse and reverse of my design printed thereon.

15 The design is for a pattern of a doll, which is shown in the form of a negro boy dressed as hereinafter specified; and it will be understood that the several garments as well as the hands, face, hair and other parts may have 20 suitable and appropriate colors with the object of further carrying out this idea.

My design consists in a pattern as shown, wherein b^2 represents the cap; C the shirt or jacket having buttons c down the center of 25 its front, upright lines c' in front and rear to represent folds or plaits, arms c^4 having wrist bands c^5 above which are short lines c^6 also representing plaits, a collar c^2 , and a necktie c^3 ; D the short trousers or knickerbockers

having buttons d at the hips and d' at the 30 knees and having lines d^2 to indicate side seams down the legs and d^3 to indicate trimming around the lower ends; E the stockings; and e the shoes having buttons e' .

In the drawing the obverse A' and reverse 35 A² are shown as printed on a single piece of fabric A, and the entire contour of each is surrounded by a broken line a situated near and everywhere approximately parallel therewith to indicate the line on which the pattern 40 shall be cut out.

This design for a pattern for printed fabrics is extremely pleasing in appearance, and is obviously intended for application to fabric to be sold and afterward made up into a doll. 45

What I claim is—

The design for a pattern for printed fabrics, substantially as herein shown and described.

In testimony whereof I have hereunto signed my name, in the presence of two attesting witnesses, at Syracuse, in the county of 50 Onondaga, in the State of New York, this 11th day of August, 1893.

IDA A. GUTSELL.
